(57) **CLAIM**

The ornamental design for a broadband adjustable match dipole antenna for embedded applications, as shown and described.

DESCRIPTION

FIG. 1 is a top perspective view of a broadband adjustable match dipole antenna for embedded applications showing our new design;

FIG. 2 is a top plan view thereof;

FIG. 3 is a right side elevational view thereof;

FIG. 4 is a left side elevational view thereof;

FIG. 5 is a front elevational view thereof;

FIG. 6 is a rear elevational view thereof; and,

FIG. 7 is a bottom plan view thereof.
